(57) **CLAIM**

The ornamental design for a folding cart, as shown and described.

DESCRIPTION

FIG. 1 is an enlarged rear view of a folding cart in an unfolded configuration;

FIG. 2 is a top view of FIG. 1;

FIG. 3 is a left-hand side view of FIG. 1;

FIG. 4 is an enlarged front view of FIG. 1;

FIG. 5 is a bottom view of FIG. 1;

FIG. 6 is a top perspective view of FIG. 1;

FIG. 7 is an enlarged rear view of the folding cart in a folded configuration;

FIG. 8 is an enlarged top view of FIG. 7;

FIG. 9 is an enlarged right-hand side view of FIG. 7;

FIG. 10 is an enlarged top perspective view of FIG. 7;

FIG. 11 is an enlarged rear and top perspective view of the front wheels portion of the folding cart; and,

FIG. 12 is an enlarged, exploded, rear and top perspective view of the right-hand, rear wheel portion of the folding cart. The broken lines shown in FIGS. 11 and 12 indicate these illustrations as being enlarged partial views and the broken lines for no part of the claimed design.

1 Claim, 12 Drawing Sheets
